UNITED STATES PATENT OFFICE.

JENKYN EDWARDS, OF HANLEY, ENGLAND.

DESIGN FOR A BOOK OR MUSIC SUPPORT.

SPECIFICATION forming part of Design No. 29,533, dated October 25, 1898.

Application filed July 15, 1898. Serial No. 686,062. Term of patent 3½ years.

To all whom it may concern:

Be it known that I, JENKYN EDWARDS, a subject of the Queen of Great Britain, residing at Hanley, Stafford county, England, have 5 invented or produced a new and original Design for Book or Music Stands, of which the following is a full, clear, and exact specification.

The object of my design is to provide a novel book and music stand which is ornamental and presents a characteristic and distinguishing appearance.

The design is illustrated in the accompanying drawings, in which—

5 Figure 1 is an edge view, and Fig. 2 a front view.

The leading feature of the design is a book and music support consisting of a broad flat central surface, with the end portions thereof 10 reversely coiled and the coils extending across

the entire width of the end portions of the flat central surface.

The letter *a* indicates the broad flat rectangular central surface, and *b b'* the reverse volute coils, which extend continuously across 25 the entire width of the end portions of said flat central surface.

My design provides a book and music support which is ornamental and characteristic in appearance. 30

What I claim is—

The design for a book and music support as herein shown and described.

In testimony whereof I have hereunto set my hand in presence of two subscribing witnesses. 35

JENKYN EDWARDS.
